UNITED STATES PATENT OFFICE.

JULES EUGÈNE MALIVERT, OF PARIS, FRANCE, ASSIGNOR OF ONE-HALF TO LOUIS BOUSQUET, OF PARIS, FRANCE.

STARTING EXPLOSION-ENGINES.

947,021.

Specification of Letters Patent. Patented Jan. 18, 1910.

Application filed March 6, 1909. Serial No. 481,570.

To all whom it may concern:

Be it known that I, JULES EUGÈNE MALIVERT, a citizen of the French Republic, residing at 32 Rue Pergolèse, Paris, France, have invented certain new and useful Improvements in Starting Explosion-Engines, of which the following is a full, clear, and exact description.

This invention relates to a method of automatically starting multicylinder explosion engines by means of compressed air. This method which effects the starting of the engine by the admission to the cylinder of a charge of compressed air upon the stroke in which the explosion would normally be taking place in the known manner, is characterized by the arrangement of a diaphragm valve for each cylinder for the purpose of admitting compressed air from a receiver, the operation of these diaphragm valves at the correct moment for each cylinder being determined by a distributor in constant relation with the engine shaft, normally maintaining upon the diaphragms a pressure of compressed air which balances the diaphragm and keeps the valve closed, and releasing this balance pressure when compressed air is to be admitted to the cylinder.

The invention is hereafter described with reference to the annexed drawings, in which:—

Figure 1 represents in section the diaphragm valve provided for each cylinder, which under the control of the distributor effects the admission of compressed air thereto at the correct moment. Fig. 2 shows separately a metallic diaphragm. Figs. 3 and 4 represent in longitudinal and transverse section the distributor which controls the operation of the diaphragm valves. Fig. 5 represents diagrammatically the application of the invention to a four cylinder engine. Fig. 6 shows the non-return valve inserted in the air-passage from each diaphragm valve to the corresponding cylinder. Figs. 7, 8 and 9 represent a valve arrangement for starting by means of the initial admission of compressed air to the starting devices; this valve is controlled from a distance by means of compressed air by a small device consisting of a miniature distributor or controller. Fig. 10 represents another type of starting valve with compressed air control and screw cut out. Fig. 11 represents a modified arrangement of controller

for the starting valve. Fig. 12 represents another form of double starting valve.

The diaphragm valve provided for each cylinder and controlling the admission of compressed air thereto is represented in Fig. 1.

A is a metal body having two unions, one ³⁵ a for the entry of compressed air from a receiver, the other a' for its exit toward the engine cylinder.

A valve b obstructing the passage between a and a' is fixed to a flexible membrane or diaphragm B of rubber, undulated sheet metal (Fig. 2) or other suitable material. This membrane is supported between the body A and a cap a² screwed thereon and carrying the union a² connected to the distributor which maintains or releases a pressure of compressed air upon the face of the membrane B on the side of the union a². A spring b' presses upon the membrane B to hold the valve upon its seat. The working of this device is as follows: If compressed air is admitted at a, it tends to raise the valve b, deflecting the membrane B and the ⁷⁰ weaker spring b', and it escapes at a'. But if air at the same pressure is admitted through the union a², the membrane B is subjected on one side to the action of the spring b' and the compressed air entering at ⁷⁵ a² over its whole upper surface, and on the other side to the air entering at a and acting upon the valve b of which the area is less than that of the membrane. The latter remains therefore in the position of closure ⁸⁰ of the valve b, even if leakage takes place and air passing around the valve acts upon the lower face of the membrane so as to balance the pressure upon the other face, for the spring b' however weak supplies the ⁸⁵ required difference to insure closing.

It will be seen that to cause the closing or opening of the valve b it suffices to admit at the union a² air of the same pressure as that admitted at a or to produce a fall of pressure upon the surface of the membrane on the side of this union a², which latter effect is obtained by placing it in communication with the atmosphere.

Since the admission of compressed air for ¹⁰⁵ starting a multi-cylinder engine operating upon a four-stroke cycle takes place only upon the third stroke and during a comparatively small part of the stroke, it suffices for obtaining this admission of air to ¹¹⁰

provide for each cylinder a diaphragm valve such as that which has been described (Fig. 1). The unions a are connected to a common compressed-air pipe coming from a receiver, and the unions a^2 to a suitable distributor such as that hereafter described; the unions a' lead to the respective cylinders through non-return valves.

The distributor connected to the unions a^2 is intended to place each of the diaphragm valves at the desired moment in communication at their face on this side either with the source of compressed-air so as to maintain the valve b closed, so cutting off the supply of compressed air to the cylinder, or with the atmospheric pressure to allow the raising of the valve by the compressed air which passes from a to a' and so to the corresponding cylinder. This distributor, of which the construction is hereafter described, and which moreover can be made in accordance with various modifications, is analogous in a general way with the distributors of known methods of starting, but it has in the present system the particular function hereafter set forth.

Figs. 3 and 4 represent such a distributor; it comprises a rotary valve driven by the engine so that the communication of the diaphragm valves with the atmosphere at their faces on the side a^2 takes place at the correct moment for each cylinder so as to cause the admission of compressed air thereto.

At 1, 2, 3, 4 are indicated the pipes which lead to the unions a^2 of the four diaphragm-valves from the four cylinders; F is the compressed air supply pipe; C indicates the rotary valve of which the spindle is geared positively to the engine by a train of wheels such as C', for example to one of the valve-shafts of the latter, so as to revolve at the desired speed ratio! This valve comprises two channels as shown so as to place successively each of the pipes 1, 2, 3, 4 in communication with the atmosphere by the channel c while the three others are in communication with the source of compressed air through the grooves c' .

The general application to the engine is effected as shown diagrammatically in Fig. 5. D' D² D³ D⁴ are the four cylinders of the engine. Each of them is provided with the diaphragm-valve device through which it receives compressed air. This device can be fixed directly upon the cylinder or for facility in erection the four devices can be grouped two and two, as shown on the drawing, A' A² on one side and A³ A⁴ on the other. d' d² d³ d⁴ are the four pipes connecting the cylinders to the unions a' of the four diaphragm-valves, through a non-return valve E on each cylinder. Fig. 6 shows in section and by way of example the construction of one of the valves E, which presents no special feature. C indicates the

rotary distributor connected on one side by four pipes c' c² c³ c⁴ to the unions a^2 of the four diaphragm-valves A' A² A³ A⁴, and on the other side by a pipe F to the source of compressed air; the latter represented by the reservoir G, is connected by the pipe H to the unions a of the diaphragm-valves A' A² A³ A⁴. Upon the pipe H is placed an ordinary stop-cock R and a second stop-cock or valve I which can be operated directly by hand by the lever i or by a remote-control device hereafter described.

The operation is as follows:—For any stopping position of the engine, the distributor C, which has been stated to be in positive relation with the engine shaft, occupies a position in which three of the diaphragm-valves A' A² A³ A⁴ are through their unions a^2 in communication with three of the pipes c' c² c³ c⁴ of the distributor C, the fourth being in communication with the atmosphere. The cylinder corresponding to this last diaphragm-valve will receive compressed air and initiate the starting of the engine. When the valve or cock I is opened for this purpose, compressed air from the reservoir G passes through the pipe F to the distributor C and through the pipe H to the devices A' A² A³ A⁴. Through the distributor C the compressed air passes along three of the tubes c' c² c³ c⁴ to the unions a^2 of the three diaphragm-valves which are not in communication with the atmosphere and acting upon the faces of their membranes B on the side of the union a^2 maintain their valves b closed. As regards the fourth diaphragm valve, its membrane B is at its face on the side of the union a^2 placed at atmospheric pressure; the air arriving at a and acting upon its valve b , i. e. its other face, opens the latter and passes at a' to the cylinder, which by reason of the timing of the distributor is upon the third or explosion stroke; the engine therefore commences to revolve and air is supplied successively to the four cylinders by the action of the distributor C which places the four diaphragm-valves in turn at atmospheric pressure on the side of their unions a^2 and so allows the passage of compressed air from the union a to the union a' and to the corresponding cylinder.

In certain applications, it may be advisable, if the cock or valve I must be placed in position inaccessible directly or by a mechanical transmission, to control this valve from a distance, likewise by means of compressed air.

Fig. 7 represents an arrangement devised for this purpose. It consists of a valve controlled by a cock in a manner similar to the diaphragm-valve shown in Fig. 1. The apparatus comprises a body J having a union i for the main air supply from the reservoir and a union j' to which is connected the pipe

H by which the air passes to all the parts A' A² A³ A⁴; the air flows from the union *j* to the union *j'* through the valve *k* attached to the membrane K. The latter is subjected 5 upon the valve side to the pressure of the compressed air and to a spring *k'*; on the other face it can be subjected either to the pressure of the compressed air or to the atmospheric pressure by means of a small distributor L which constitutes the controller, and to which it is connected by a pipe M. This small distributor is shown in Figs. 8 and 9 and has a function analogous to that of the distributor C. If compressed air is 15 supplied at *j*, owing to the difference of the areas of the membrane K and the valve *k* the latter is maintained upon its seat, if there is no pressure on the other face of the membrane. But if by operating the valve *l'* 20 of the small distributor L connected at *l* to the source of compressed air and at *m* to the pipe M, air at the same pressure is admitted upon the upper face of the membrane K, the equilibrium is broken, the valve *k* opens and 25 the main air flows from *j* to *j'* toward the diaphragm valves A' A² A³ A⁴ of the cylinders, the valve *k* remaining open so long as the air pressure is maintained by the small distributor L. When the latter is operated 30 to stop this admission and the said face of the membrane K is returned to the atmospheric pressure by the channel *l'* of the small distributor, the compressed air from *j* pressing beneath the membrane K will automatically 35 reclose the valve *k*.

Fig. 10 shows a modification of the valve represented in Fig. 7 and of which the function is similar to that described, but it comprises in addition a screw N which allows 40 of pressing the valve *k* tightly against its seat when the apparatus is not to be employed. These pneumatic controls for the main inlet valve allow of having operating devices of very small size and requiring less 45 exertion from the operation.

Fig. 11 shows a modification of the small distributor of Fig. 8, arranged with lift-valves instead of a rotary valve. This apparatus comprises a body O, a valve P, a 50 spring *p*, and an operating handle Q carrying a valve *q*; a rubber washer *q'* forms a packing. Compressed air taken from the main pipe arrives at *l*; it flows to *m* only when the handle Q is pushed. The valve *q* resting then upon its seat, raises the valve 55 P and compressed air passes out at *m* toward the valve shown in Fig. 7 or 10, a small channel *q''* placing the base of the valve *q* in communication with the atmosphere. 60

Fig. 12 shows a cock combining in one the two valves I and R indicated in Fig. 5, that is the valve or cock which is operated directly or indirectly to obtain the start, and 65 the auxiliary stop-cock. This apparatus

comprises a body O, a valve T with a stem having on one side a guiding square *t* and on the other a threaded portion *t'* screwing into the stem *u* of the operating handle U; *t''* is a recoil spring. The stem *u* comprises 70 a collar *u'*. Admission of air takes place at *g* and outlet at *h*. The valve I cannot turn but only move longitudinally being guided by the sliding square; if the hand-wheel U is turned to screw the stem *u* until the collar *u'* 75 contacts with the body, the valve T is pressed and locked upon its seat, and the device thus serves as a stop-cock like the cock R in Fig. 5. To cause this device to act as a starting valve like the cock I, the wheel U is turned 80 to unscrew and free the collar *u'*; it then suffices to press upon the wheel U as on a button to release the valve T from its seat and cause the passage of compressed air.

The invention can of course be carried out 85 with all modifications consonant with the general arrangements set forth and is not limited to the constructional details represented.

The invention has been described in its 90 application to a four-cylinder engine, but can of course be applied to an engine of a greater number of cylinders, the distributor being arranged in a corresponding manner. 95

Having thus described my invention, what I claim as such and desire to secure by Letters Patent is:—

1. The combination with an explosion engine having a plurality of cylinders, of a 100 plurality of sources of fluid under pressure, a valve casing for each cylinder and communicating therewith and communicating with both of said sources, a valve for closing the communication between one of said 105 sources and the cylinder, a diaphragm in the casing for controlling the valve and arranged between the port leading to the other source and the port leading to the cylinder, one face of the diaphragm being subject to 110 the pressure from the other source and the other to the pressure of the cylinder, and a rotating valve driven by the engine for successively interrupting the communication 115 between the said other source and the valve casings.

2. The combination with an explosion engine having a plurality of cylinders, of a plurality of sources of fluid under pressure, a valve casing for each cylinder and communicating therewith and communicating with both of said sources, a valve for closing the communication between one of said 120 sources and the cylinder, a diaphragm in the casing for controlling the valve and arranged between the port leading to the other source and the port leading to the cylinder, one face of the diaphragm being subject to 125 the pressure from the said other source and the other to the pressure of the cylinder, and 130

- means operated by the engine for successively interrupting the communication between said other source and the valve casings.
3. The combination with an explosion engine having a plurality of cylinders, of a plurality of sources of fluid under pressure, a valve casing for each cylinder and communicating therewith and communicating with both of said sources, a valve for closing the communication between one of said sources and the cylinder, a diaphragm in the casing for controlling the valve and arranged between the port leading to the other source and the port leading to the cylinder, one face of the diaphragm being subject to the pressure from said other source and the other to the pressure of the cylinder, a rotating valve driven by the engine for successively interrupting the communication between the said other source and the valve casings, and a manually operated valve for controlling the communication between the said other source and the rotating valve.
4. The combination with an explosion engine having a plurality of cylinders, of a plurality of sources of fluid under pressure, a valve casing for each cylinder and communicating therewith and communicating with both of said sources, a valve for closing the communication between one of said sources and the cylinder, a diaphragm in the casing for controlling the valve and arranged between the port leading to the other source and the port leading to the cylinder, one face of the diaphragm being subject to the pressure from the said other source and the other to the pressure of the cylinder, a rotating valve driven by the engine for successively interrupting the communication between the said other source and the valve casing, a valve controlling the communication between the said other source and the rotating valve, means remote from the said valve for controlling the same and means for cutting out the said means.
- the other to the pressure of the cylinder, a rotating valve driven by the engine for successively interrupting the communication between the said other source and the valve casings, a valve controlling the communication between the said other source and the rotating valve, and means remote from the said valve for controlling the same.
5. The combination with an explosion engine having a plurality of cylinders, of a plurality of sources of fluid under pressure, a valve casing for each cylinder and communicating therewith and communicating with both of said sources, a valve for closing the communication between one of said sources and the cylinder, a diaphragm in the casing for controlling the valve and arranged between the port leading to the other source and the port leading to the cylinder, one face of the diaphragm being subject to the pressure from the said other source and the other to the pressure of the cylinder, a rotating valve driven by the engine for successively interrupting the communication between the said other source and the valve casing, a valve controlling the communication between the said other source and the rotating valve, means remote from the said valve for controlling the same and means for cutting out the said means.

In testimony whereof I have signed my name to this specification, in the presence of two subscribing witnesses.
